(57) **CLAIM**

The ornamental design for a shaving razor storage tray with lid, as shown and described.

DESCRIPTION

FIG. 1 is a top, front, right side perspective view of a shaving razor storage tray lid with showing my new design;

FIG. 2 is an exploded top, front, right side perspective view thereof;

FIG. 3 is a bottom, rear, left side perspective view of the tray part thereof, the lid being removed for clarity of illustration; FIG. 4 is a bottom, front, right side perspective view of the tray part thereof, the lid being removed for clarity of illustration;

FIG. 5 is a top plan view of the tray part thereof, the lid being removed for clarity of illustration;

FIG. 6 is a bottom plan view of the tray part thereof, the lid being removed for clarity of illustration;

FIG. 7 is a front elevation view of the tray part thereof, the lid being removed for clarity of illustration;

FIG. 8 is a rear elevation view of the tray part thereof, the lid being removed for clarity of illustration;

FIG. 9 is a right side elevation view of the tray part thereof, the lid being removed for clarity of illustration;

FIG. 10 is a left side elevation view of the tray part thereof, the lid being removed for clarity of illustration;

FIG. 11 is an exploded top, front, right side perspective view thereof, with a shaving razor placed in the tray and fluid surrounding the shaving razor cartridge;

FIG. 12 is a top, front, right side perspective view thereof, with a shaving razor placed in the tray;

FIG. 13 is a top plan view thereof;

FIG. 14 is a front elevation view thereof;

FIG. 15 is a rear elevation view thereof;

FIG. 16 is a right side elevation view thereof;

FIG. 17 is a left side elevation view thereof;

FIG. 18 is a top, front, right side perspective view of the lid part thereof, the tray being removed for clarity of illustration;

FIG. 19 is a bottom, front, right side perspective view of the lid part thereof, the tray being removed for clarity of illustration;

FIG. 20 is a top plan view of the lid part thereof, the tray being removed for clarity of illustration;

FIG. 21 is a bottom plan view of the lid part thereof, the tray being removed for clarity of illustration;

FIG. 22 is a rear elevation view of the lid part thereof, the tray being removed for clarity of illustration;

FIG. 23 is a front elevation view of the lid part thereof, the tray being removed for clarity of illustration;

(Continued)

FIG. 24 is a right side elevation view of the lid part thereof, the tray being removed for clarity of illustration; and, FIG. 25 is a left side elevation view of the lid part thereof, the tray being removed for clarity of illustration. The broken line showing in the figures is included for the purpose of illustrating portions of the razor storage tray with lid and form no part of the claimed design.
